US0D1072261S

(12) **United States Design Patent** (10) **Patent No.:** **US D1,072,261 S**
(45) **Date of Patent:** **** Apr. 22, 2025**

(54) **APPARATUS FOR THERMOTHERAPY**

(71) Applicant: **CERAGEM CO., LTD.**, Cheonan (KR)

(72) Inventor: **Choi Sang Ho**, Cheonan (KR)

(**) Term: **15 Years**

(21) Appl. No.: **29/860,319**

(22) Filed: **Nov. 17, 2022**

(51) **LOC (15) Cl.** **24-01**
(52) **U.S. Cl.**

USPC **D24/206**

(58) **Field of Classification Search**

(57) **CLAIM**

The ornamental design for an apparatus for thermotherapy, as shown and described.

DESCRIPTION

FIG. 1 is a front, left perspective view of an apparatus for thermotherapy showing the claimed design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The evenly spaced broken lines illustrate portions of the apparatus for thermotherapy, forming no part of the claimed design. The dot-dashed broken lines illustrate boundaries to the claim that form no part of the claimed design.

1 Claim, 7 Drawing Sheets
